ELECTRIC SOCKET

John M. Roper, Washington, D. C.

Application August 4, 1936, Serial No. 94,182

2 Claims. (Cl. 173—328)

(Granted under the act of March 3, 1883, as
amended April 30, 1928; 370 O. G. 757)

This invention relates to a single contact electric socket and has for an object to provide improved electrical sockets especially useful on aircraft, both of the lighter and heavier than air type, where the economy of space and weight are desirable features.

A further object of this invention is to provide an electrical socket especially adapted for holding electrical lamps of the bayonet joint type for use 10 on vehicles of all descriptions, both vehicles used in the air, on the ground, on the water, and under the water.

A further object of this invention is to provide a lamp socket occupying a minimum amount of 15 space and weight which will be especially useful on vehicles such as aircraft, and more particularly, on the wing surfaces and edges, so as to receive and hold a lamp in such positions without seriously affecting the aerodynamic characteristics of the wing surfaces.

A still further object of this invention is to provide a single contact lamp socket in combination with a metal covered conduit cable wherein the metal cover on the conduit cable acts as a ground 25 or return lead for the circuit.

A still further object of this invention is to provide an electrical socket wherein the contactor terminal is yieldably held against the lamp terminal and the necessity for a surplus amount of wire 30 normally present with yieldable contacts is eliminated as a result of the improved features of this invention.

A still further object of this invention is to provide an electrical socket in which the lamp is 35 fixedly secured and in which the terminal end of the conductor cable is yieldably held by a compression spring acting between a terminal insulation member and an inturned flange on the socket.

With the foregoing and other objects in view, the invention consists in the construction, combination and arrangement of parts, as will be described more fully hereafter.

In the drawing:

The single figure is a sectional view of the invention.

There is shown at 10 the electrical socket of this invention. This electrical socket includes a socket member 11 shaped preferably as shown, 40 having bayonet slots 12 to provide for the reception of the base of a conventional single contact electric lamp 13, the lamp 13 having its contact as at 14. The lower end of the socket 11 is inturned as at 15, and through the socket 11 extends the conduit 16 for the conductor cable 17

having the stranded wires 18 therein. A ferrule 19 having an outwardly extending flange 20 is secured on the upper end of the metal cable conduit 16. The stranded wires 18 are soldered as at 21 into a terminal 22, the terminal 22 being formed on an insulating collar 23, it being observed that the cable 17 and stranded wires 18 extend through the center of the collar 23 and that the diameter of the collar 23 is such that it will just snugly and slidably fit within the socket 10 11. A compression spring 24 placed between the inturned flange 15 of socket 11 and the flange 20 of ferrule 19 urges the insulating collar 23 and terminal 22 against the lamp contact 14.

The invention thus constructed is extremely 15 light in weight and at the same time occupies only a minimum of space, which features are extremely desirable when used on aircraft. When used in running lights, as on wing surfaces, the lamp is held close to the wing surface to cause 20 a minimum of interference with the aerodynamic characteristics thereof.

As an exemplification of the manner in which this invention is applied, the socket 11 is provided with an outstanding collar 25 provided with 25 a shoulder, as at 26. A nut 27 passes over the collar 25 and holds a globe reflector foundation 28 thereon by means of the threaded neck 29 extending therebelow, the neck 29 being provided with a kerf 30 fitting over a key 31 so as 30 to properly position the foundation 28 against rotation.

A reflector 32 is snapped over an internal neck 33 of the foundation 28 while a globe 34 is threaded into an external neck 35, a cushioning 35 washer 36 being provided for the globe 34 to seal thereagainst. Lamp sockets with fixed conductor terminals and yieldable lamp terminals have been used for above purpose, but it has been found that the vibration thereof induced during 40 flight caused the contacts to wear away so quickly that the lamp soon fails to light. With the arrangement of this invention, however, such objectionable vibration has been eliminated.

Other modifications and changes in the proportions and arrangements of the parts may be made by those skilled in the art without departing from the nature and scope of the invention, as defined in the appended claims.

The invention described herein may be manufactured and used by or for the Government of the United States of America for governmental purposes without the payment of any royalties thereon or therefor.

Having thus set forth and disclosed the nature of this invention, what is claimed is:

- 5 1. An electric lamp socket comprising a socket member having an inturned apertured flange at one end thereof, the other end of said socket being provided with lamp base securing means, an electric cable conduit extending through said apertured flange into said socket, a ferrule secured on the end of said cable conduit within 10 said socket, said ferrule having an out-turned flange at the end thereof, a compression spring located between said ferrule flange and said in-turned socket flange, an insulating member resting against said ferrule flange, a conductor cable 15 extending through said cable conduit and into said insulating member, and a cable terminal extending above said insulating member, said cable being secured to said terminal within said insulating member, whereby said cable conduit 20 is yieldably secured to yieldably press said cable terminal against a lamp contact in the lamp base adapted to be held at the lamp end of the socket, said cable including an insulation covered stranded conductor wire extending therethrough, 25 the end of said conductor wire being soldered within said terminal.

2. An electric lamp socket comprising a socket

member having an inturned apertured flange at one end thereof, the other end of said socket being provided with lamp base securing means, an electric cable conduit extending through said apertured flange into said socket, a ferrule secured on the end of said cable conduit within said socket, said ferrule having an out-turned flange at the end thereof, a compression spring located between said ferrule flange and said in-turned socket flange, an insulating member resting against said ferrule flange, a conductor cable 10 extending through said cable conduit and into said insulating member, and a cable terminal extending above said insulating member, said cable being secured to said terminal within said insulating member, whereby said cable conduit is yieldably secured to yieldably press said cable terminal against a lamp contact in the lamp base adapted to be held at the lamp end of the socket, said conductor cable including an insulation covered stranded conductor wire extending therethrough, the end of said conductor wire being soldered within said terminal, the inturned apertured flange of said socket member being an 15 integral part thereof.

JOHN M. ROPER.
